ABSTRACT

A switching circuit for enabling a selected one of a number of channels. The circuit includes a number of devices, one for each channel, each having a voltage-/current characteristic with a negative-impedance region separating two stable states. The devices are fed in parallel from a source of constant current or constant voltage of a magnitude such that only one may assume one of the stable states. The devices may be for example programmable unijunction transistors or tunnel diodes.

ELECTRONIC SWITCHING APPARATUS

This invention relates to electronic switching apparatus.

An object of the invention is to provide a switching apparatus for selecting one or more channels from a number of similar channels and which is small, efficient, versatile and reliable and has a low power dissipation.

According to one aspect of the present invention there is provided an electronic switching apparatus including a plurality of electronic devices for switching selected ones of a corresponding plurality of channels, each of said devices being connected in series with a load in such a way that it can have only two stable states, the devices being arranged for connection to a constant-voltage or constant-current so that only a predetermined number of the devices can exist in one stable state, means associated with each device for altering its condition to temporarily make only said one stable state available whereby another of the devices is driven to its other stable state, and a monitor associated with each device arranged to monitor which of its stable states it occupies.

Preferably the devices have an output characteristic which includes a negative impedance region.

The invention also provides an electronic switching apparatus including a plurality of programmable unijunction transistors (PUTs) for switching selected ones of a plurality of channels, a load in series with each PUT to define high and low stable states of voltage and current of the PUT, the series combinations of PUTs and loads being connected together in parallel for connection to a constant current source whose current is sufficient to maintain only a predetermined number of PUTs in the high state, means for applying a controlled voltage across the cathode and gate of each PUT, and means for monitoring each PUT to determine which of its stable states it occupies at any given time.

Preferably, the means for applying a controlled voltage comprises a first Zener diode arranged to normally determine the cathode-gate voltage of each PUT, and a second Zener diode of lower breakdown voltage arranged to be selectively shunted across the first Zener diode.

Preferably also, the first and second Zener diodes are arranged to control a transistor regulating the cathode-gate voltage of the relevant PUT.

The second Zener diode may be shunted across the first by a push-button or by a switching transistor.

An embodiment of the invention will now be described by way of example, with reference to the accompanying drawings, in which:

FIG. 1a illustrates a circuit incorporating a programmable unijunction transistor (PUT);

FIG. 1b is a graph showing the characteristics of the circuit of FIG. 1a;

FIG. 2 illustrates the basic form of an embodiment of the invention;

FIG. 3 is a more detailed illustration corresponding to FIG. 2; and

FIG. 4 shows a modification of the circuit of FIG. 3.

Referring now to FIG. 1, as is known when a voltage V_{SG} is applied in series with a resistance R_G between the gate and cathode of a programmable unijunction transistor (PUT) 10 then the voltage/current characteristic

of the PUT 10 is as shown in FIG. 1b; this characteristic has a peak voltage V_p and a valley voltage V_v separated by a negative impedance region and the value of the peak voltage V_p is governed by the cathode-gate voltage V_{SG} . FIG. 1b also shows the load line for a resistance R_A in series with the anode-cathode voltage source V_{SA} , and from this it is seen that three possible states exist for the conditions shown in FIG. 1a, namely those labelled 11, 12 and 13. The state 12 however is unstable owing to its being situated on the negative impedance region, and in practice the PUT 10 may assume either of the states 11 and 13 which are hereinafter referred to as the "low" and "high" states respectively.

Turning now to the present invention as embodied in FIGS. 2 to 4, the principle of operation may be described with reference to FIG. 2. A number of PUTs designated PUT₁, PUT₂, . . . , PUT_n are connected in parallel across a constant current source (not shown). Associated with each PUT is a series load resistor R_{A1}, R_{A2}, . . . , R_{An} and a voltage source such as V_{SG1} arranged in series with a current-limiting resistor such as R_{G1} between its cathode and gate. The current I_C delivered by the source is such that only a predetermined number (in this embodiment one) of the PUTs can be in the high state at any given time. Assume that PUT₁ is in the high state and that all the sources V_{SG1} . . . V_{SGn} are delivering the same voltage. If then the source, say, V_{SG2} is acted upon to reduce its voltage, the characteristic of the PUT₂ is altered in the manner that its peak voltage is reduced; the reduction in the voltage of the source V_{SG2} is made sufficient to bring the peak voltage of PUT₂ below the load line thus forcing PUT₂ to assume the high state. This in turn draws an increased current through PUT₂ and reduces the current available to PUT₁ which therefore moves to the low state. At this point the voltage of the source V_{SG2} may be returned to its original value, equal to that of the other sources. By monitoring the anode-cathode voltages of the PUTs a multi-channel two level output is obtained and (in this embodiment, with only one high level) the circuit functions as an EXCLUSIVE-OR device. The outputs may be used to drive any suitable form of two level switch, for example reed relays may be driven via amplifiers.

The PUTs can be easily matched by suitable selection of V_{SG} and R_G.

FIG. 3 illustrates a practical embodiment of the basic circuit of FIG. 2. Each voltage source comprises a series regulating transistor such as T₂ whose base bias is normally fixed by a resistor R₂ and a Zener diode Z₂ connected in series across power supply lines 20, 21 which are fed by a power supply separate from the constant current source for the PUTs. To select, for example, the channel of PUT₂ a pushbutton P₂ is depressed to connect a further Zener diode Z₂₂ across the diode Z₂. The reverse breakdown voltage of the further diode Z₂₂ is less than that of the diode Z₂, and thus the voltage at the gate of PUT₂ determined by T₂ is reduced and the channel controlled by PUT₂ is selected as described above. Each channel is identical, except that that of PUT₁ has a capacitor C connected across the diode Z₁. On switching on the power supply and constant current source, the cathode-gate voltage of PUT₁ is held below that of the other PUTs until the capacitor C₁ is charged, thus ensuring that PUT₁ is selected initially.

As shown in FIG. 4, the push buttons P_1 etc. may be replaced by series switching transistors, such as T_{11} , whose bases receive control pulses from a remote source, and a monitor may be connected across the anode and cathode of each PUT. As described above, 5 these monitors may consist essentially of two-level reed relays RR_1 and RR_2 driven through suitable amplifiers A_1 and A_2 .

The invention comprehends the use of devices other than programmable unijunction transistors; any device 10 having two distinct stable states may be used. It is preferred to use devices having a negative impedance region in their output characteristics, and other possible devices of this type are active amplifiers with positive feedback, and tunnel diodes.

With tunnel diodes, for example, the output characteristic is similar to that shown in FIG. 1b, but with the ordinate as current and the abscissa as voltage. In this case, the tunnel diodes are connected in series across 15 a constant-voltage source. A particular tunnel diode may be selected by connecting a shunt across it to reduce the applied current. Output may be obtained by monitoring the voltage drop across each tunnel diode, for example by means of a Schmitt trigger circuit.

As the characteristics of semiconductor devices vary 20 with temperature, temperature compensation may be provided by using a voltage or current source of a suitable temperature coefficient. Alternatively, in the embodiment of FIG. 3, it is possible to provide this by suitable choice of the temperature coefficient of the resistors R_G .

We claim:

1. An electronic switching apparatus comprising:

a plurality of programmable unijunction transistors (PUTs) connected to switch selected ones of a plurality of channels, 5 a load in series with each PUT which defines high and low stable states of voltage and current of that PUT, the series combinations of PUTs and loads being connected together in parallel, means supplying to said series combinations a constant current sufficient to simultaneously maintain only one of said PUTs in the high state, means connected to apply a controlled voltage across the cathode and gate of each PUT, and means connected to monitor each PUT to determine which of its stable states it occupies at any given time.

2. Apparatus as claimed in claim 1, in which the means for applying a controlled voltage comprises a first Zener diode arranged to normally determine the cathode-gate voltage of each PUT, and a second Zener diode of lower breakdown voltage arranged to be selectively shunted across the first Zener diode.

3. Apparatus as claimed in claim 2, in which the first and second Zener diodes are arranged to control a transistor regulating the cathode-gate voltage of the relevant PUT.

4. Apparatus as claimed in claim 2, including a push-button for selectively shunting the second Zener diode across the first.

5. Apparatus as claimed in claim 2, including a switching transistor for selectively shunting the second Zener diode across the first.
